CLAIM

The ornamental design for an LED lens, as shown and described.

DESCRIPTION

FIG. 1 is a perspective view of an LED lens showing our new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof; and,

FIG. 7 is a bottom plan view thereof.

The broken lines shown are included for the purpose of illustrating environmental structures and forming no part of the claimed design.
